UNITED STATES PATENT OFFICE.

ROBERT LOUDON WALKER, OF BOSTON, MASSACHUSETTS.

FURNACE.

SPECIFICATION forming part of Letters Patent No. 439,705, dated November 4, 1890.

Application filed February 8, 1890. Serial No. 339,005. (No model.)

To all whom it may concern:

Be it known that I, ROBERT LOUDON WALKER, of Boston, in the county of Suffolk and State of Massachusetts, have invented an Improved Furnace, of which the following is a specification, reference being had to the accompanying drawings, in which is shown a sectional elevation of a so-called "pipe-boiler" furnace embodying my invention.

10 The object of my invention is to produce a furnace which saves fuel and prevents smoke; and my invention consists in the hereinafter-described combination of a fire-box, grate, divided ash-pit, and arrangement of drafts whereby a stronger draft is passed through 15 one part of the grate than through its other part.

In the drawings, A is a boiler; B, a furnace; D, the fire-box; F F', the ash-pit, and G the grate. The air-blast chamber F' is formed by 20 a partition f, dividing the ash-pit into two chambers, and a blast is introduced into the chamber F' by any suitable means, preferably through a pipe f', which is introduced 25 at any convenient place. That portion of the grate which is over chamber F' is a shaking or like grate to keep the quick-burning fire thereon free from clinkers and to allow the accelerated draft freer passage. The ordinary draft is, as usual, through chamber F of 30 the ash-pit, and as the products of combustion under the influence of this draft pass toward the flues they pass over that portion of

the fire which is quickened by the air-blast from chamber F', whereby the smoke and 35 gases are very perfectly consumed, the products of combustion arising from the greener part of the fire being directed by a deflector H, mounted above grate G, upon the quickened portion of the fire.

I do not claim herein the combination of a deflector with a grate, a portion of which may be shaken independently of its other portion, as that combination is set forth and claimed in my application, Serial No. 343,143, filed 45 March 8, 1890.

What I claim is—

In a furnace, the combination of a fire-box, grate, and ash-pit divided into two chambers, with a deflector and means substantially such 50 as described—for example, a forced draft—for causing a draft through one part of the grate greater than the draft through the other part of the grate, that part of the grate through which the stronger draft passes being a shaking grate, and the deflector being arranged over the grate to direct products of combustion arising from the fire on that part of the grate through which the weaker draft passes over the fire on that part of the grate through 55 which the stronger draft passes, substantially as and for the purpose set forth.

ROBERT LOUDON WALKER.
